CLAIM

The ornamental design for a combined support and cover for a watering cup, as shown and described.

DESCRIPTION

FIG. 1 is a front elevational view of a combined support and cover for a watering cup showing my new design;
FIG. 2 is a right side elevational view thereof;
FIG. 3 is a left side elevational view thereof;
FIG. 4 is a rear elevational view thereof;
FIG. 5 is a top plan view thereof; and,
FIG. 6 is a bottom plan view thereof.
The broken lines in FIGS. 1 through 6 are for purposes for illustration only and form no part of the claimed design.

FIG. 1

FIG. 3

FIG. 4

FIG. 6
